WELL TOOL

Raymond G. Taylor, Jr., Dallas, Tex., assignor to
 The Gulberson Corporation, Dallas, Tex., a
 corporation of Delaware

Application October 28, 1942, Serial No. 463,717

13 Claims. (Cl. 166—2)

The invention relates to a retrievable well tool, such as, for instance, a bottom hole choke and is adapted for use in a string of tubing in an oil well. This tubing is provided with joints, the ends of the tubing being separated slightly and connected by an outside collar, thereby forming an annular channelway between the sections of the tubing. The invention relates to utilizing this annular channelway as a means to anchor the retrievable bottom hole choke.

Another object of the invention is the provision of a well tool which may be lowered into the tubing by a wire line, and after the well tool has been anchored in the tubing, the wire line and certain parts carried thereby may be removed from the well, leaving the well tool securely positioned at the desired point in the tubing.

Another object of the invention is the provision of means to retrieve the well tool so that it can be removed from the well.

Another object of the invention is the elimination of all shear pins or other parts which must be broken in order to position the well tool in the well or to remove it therefrom.

Another object of the invention is to provide a strong, sturdy device which is simple in construction, easy to manufacture with parts which can be easily replaced, if this should be necessary on account of wear or damage, and the elimination of complicated structure which might easily become damaged or require constant adjustment.

Other objects and advantages of the invention will appear in the detailed specification and claims which follow.

The invention may be better understood by referring to the attached drawings, in which

Figure 1 is an elevational view partly in cross-section, and showing the tool and the relative position of the parts thereof in the condition in which they would be while the tool is being run into the well.

Figure 2 is a view similar to Figure 1, but showing the running-in mechanism unlatched from the well tool just prior to the running-in tool being lifted from the well tool.

Figure 3 is an elevational view, partly in cross-section, of the well tool with the running-in mechanism removed therefrom and with the well tool locked in the well tubing.

Figure 4 is an elevational view, partly in cross-section, showing the well tool with a retrieving tool latched thereto with the inner mandrel being pulled from behind the locking dogs, and

Figure 5 is a cross-sectional view taken on the line 5—5 of Figure 2.

Referring to Figures 1 and 2, a running-in mechanism supports the well tool and the entire assembly is lowered into the tubing 1 by means of a wire line 2. The wire line supports the running-in mechanism which includes a socket 3 which supports a rod 4, on which a collar 5 is slidable. Attached to the collar 5 are springs 6 which are bowed outwardly and contact the inner surface of the tubing so as to create a drag. The lower ends of the springs 6 are secured to a hollow sleeve 7 which is provided at its lower end with an inwardly extending cam surface 8. As the parts are lowered in the tubing, the friction between the springs 6 and the tubing 1 causes the sleeve 7 to rest against the stop at the lower end of the socket 3, as is shown in Figure 1. The rod 4 carries at its lower end a latch member 9 which, at its lower end, forms a sleeve 10. The member 9 is provided with a diametrically extending channelway which receives a slide pin 11 provided with a cam head 12. A spring 13 urges the said pin to the right, as viewed in Figure 1, so that the head projects outwardly from the member 9 so that it would be engaged by the cam surface 8, if the members 7 and 9 moved relative to each other a sufficient extent to cause such engagement. The slide pin 11 carries a latch 14 which protrudes through a hole in the sleeve 10, and so that it will underlie a shoulder 15 carried by a mandrel 16 comprising part of a retrievable well tool.

The mandrel 16 is provided with a longitudinally extending bore 17 through which well liquid may pass. The mandrel is also provided with an intermediate shoulder 18 so that the section thereof above the shoulder 18 is of lesser diameter than the section below the said shoulder.

A sleeve 19 surrounds a portion of the mandrel 16. This sleeve is provided with a shoulder 20, and the mandrel is provided with a shoulder 21. A coil spring 22 is positioned between the shoulders 20 and 21 so as to urge the mandrel 16 downwardly relative to the sleeve 19. The sleeve 19 is provided with an annular channelway 23, and the lower portion of the sleeve 10 is provided with holes 24 which receive steel balls 25. When the parts are in the position shown in Figure 1, the upper end of the mandrel 16 is positioned within the sleeve 10 and the mandrel holds the balls 25 in the holes 24 and channelway 23, so that the sleeve 19 is thereby locked to the sleeve 10, and it will be remembered that the latch 14 is latching the latch member 9 to the

mandrel 16 so that when the parts are in this position, there can be no relative movement between the mandrel 16, the sleeve 19 and the running-in mechanism.

The lower end of the mandrel 16 is provided with a cam surface 26 which, when the parts are in the position shown in Figure 1, is positioned slightly above two dogs 27 which are pivoted by pins 28 to the sleeve 19. The sleeve 19 is provided with recesses 29 in which these dogs are positioned. Each of the dogs is provided with an arcuate channel section 30, and the sleeve 19 is provided with channels, section 30 adapted to register with channel section 30 in the dogs, and a garter spring 31 passes circumferentially around the dogs and the sleeve 19, and is positioned in the channel 30. This spring tends to hold the said dogs in their retracted positions, as shown in Figure 1. The sleeve 19 continues downwardly a short distance below the said dogs and is secured to a hollow sleeve 32 which carries a sealing cup 33. The sleeve 32 is connected by a collar 34 to a choke 35.

The running-in mechanism includes the parts shown in Fig. 1, which support the parts shown in Fig. 3, and which may be removed from the well, leaving the well tool in the well tubing. The well tool includes the parts which may be anchored in the well and left therein when the running-in tool is removed.

As shown in Figure 1, the running-in tool and the retrievable well tool are all lowered into the tubing by the wire line 2, with the collar 5 resting against the lower end of the socket 3. There is little, if any, relative movement between any of the parts as the running-in mechanism and retrievable well tool are lowered in the tubing 1.

Succeeding sections of the tubing 1 are slightly spaced apart and are connected by a collar 36 forming an annular channelway 37.

When it is desired to set the retrievable choke in the tubing, the wire line is raised. The drag between the spring 6 and the tubing 1 causes the collar 5 and sleeve 7 to tend to remain stationary relative to the tubing, so that the latch member 9 is moved upwardly into the hollow section of the sleeve 7, resulting in the head 12 of the slide pin 11 engaging the cam surface 8 and moving the pin 11 to the left, as viewed in Figures 1 and 2, thereby retracting the latch 14 from beneath the shoulder 15 of the mandrel 16. The spring 22 is now free to move the mandrel 16 downwardly relative to the sleeve 19, so that the smaller diameter portion of the mandrel 16 above the shoulder 18 will now be behind the steel balls 25, thereby allowing the steel balls to move inwardly out of the channelway 23 and thereby release the sleeve 10 forming a part of the running-in tool from the sleeve 19 forming a part of the retrievable choke. However, the spring 22 cannot move the sleeve 16 downwardly so as to position it behind the dogs 27 unless the dogs are adjacent one of the channelways 37 in the tubing, for there is not sufficient clearance between the lower section of the mandrel and the tubing to permit actuation of the dogs 27 except at the channelway 37 at one of the tubing joints. It is only at this point that the dogs 27 can move outwardly against the tension of the spring 31 a sufficient distance to allow the lower portion of the mandrel to be positioned behind said dogs. Therefore, if the operator should attempt to set the retrievable well tool at a point other than a tubing joint, the steel balls 25 would not be unlocked until the dogs had been raised or

lowered to a point adjacent the channelway 37, whereupon the cam surface 26 would move these dogs outwardly as the spring 22 moves the mandrel downwardly so that the parts would then be in the position shown in Figure 2. At this time the steel balls 25 would be released so that the running-in mechanism would be released from the well tool and could be raised to the surface of the well, leaving the retrievable well tool in the well, as is shown in Figure 3.

When it is desired to remove the retrievable well tool from the well, a retrieving mechanism is lowered on a wire line 38, as is shown in Figure 4. The wire line 38 supports a socket 39, which carries a rod 40 supporting a hollow sleeve 41, which has an upwardly flaring surface 42 near the lower inner portion thereof. Within the sleeve 41 are dogs 43 provided with grab teeth 44. The dogs 43 are normally urged downwardly by means of a spring 45. The retrieving tool can, therefore, be lowered into the well so that the cam surface 46 at the lower end of the sleeve 41 will center the retrieving tool relative to the mandrel 16, and so that the upper end of the mandrel will project upwardly through the dogs 43. An upward pull on the wire line 38 will cause the grab teeth 44 to clench the upper end of the mandrel 16, the flaring surface 42 urging these dogs inwardly. The mandrel 16 is now elevated as the wire line is raised, thereby moving the lower section of the mandrel from behind the dogs 27 so that these dogs will be cammed inwardly and the retrievable well tool will now be free to be raised to the surface and removed from the well.

It is realized that many changes may be made in the specific form of the invention, as shown by way of illustration herein, and I desire to claim the same broadly, reserving to myself the right to make such changes and modifications therein as may fairly fall within the scope of the appended claims.

Having now described my invention, I claim:

1. In combination, a wire line, a rod supported by said wire line, a latch member carried by said rod, said latch member including a laterally slidable pin and latch, a releasable well tool including a mandrel having a shoulder which may be engaged by said latch to support the mandrel and cam means slidable on said rod to actuate said pin to release the latch from the mandrel when the wire line is raised relative to the cam means.

2. In combination, a wire line, a rod supported by said wire line, a latch member carried by said rod, said latch member including a laterally slidable pin and latch, a releasable well tool including a mandrel having a shoulder which may be engaged by said latch to support the mandrel, a sleeve slidable on said rod and provided with a cam surface, means to hold said sleeve stationary when the wire line carrying the rod and latch member is raised, said cam surface serving as a means to actuate said pin to release the mandrel when the wire line is raised.

3. In combination, a running-in mechanism including a wire line, a rod supported thereby, a latch member carried by said rod, said latch member including a laterally slidable pin and latch, and a sleeve forming an extension of said latch member, a releasable well tool including a mandrel extending within said sleeve, and a second sleeve surrounding the mandrel, said latch serving as a means to secure the mandrel to the running-in mechanism so that the mandrel

is supported thereby, means whereby the latch is released from the mandrel when the wire line is raised relative to said means, said second sleeve being provided with a channelway, said first sleeve being provided with holes, balls held in place in said channelway and holes by said mandrel so as to lock the running-in mechanism to said second sleeve, and means tending to actuate the mandrel when it has been released so as to release the balls from said channelway so as to release the second sleeve from the running-in mechanism.

4. In combination, a hollow mandrel which may be lowered into a tubing string having annular channelways at tubing joints, a sleeve 15 slideable on said mandrel, said sleeve being provided with a plurality of recesses, dogs pivoted to said sleeve and lying partly within said recesses and means to move said mandrel relative to said sleeve, and means whereby the movement of said mandrel will move said dogs outwardly into locking engagement with the tubing joint.

5. In combination, a hollow mandrel which may be lowered into a tubing string having annular channelways at tubing joints, a sleeve 25 slideable on said mandrel, said sleeve being provided with a plurality of recesses, pivoted dogs carried by said sleeve in said recesses, a cam forming a part of said mandrel and means to move said mandrel relative to said sleeve to move said cam into engagement with said dogs to move the dogs outwardly into locking engagement with the tubing joint, the dogs having a thickness greater than the distance between the inner wall of the tubing string and the outer surface of the cam on the mandrel.

6. In combination, a hollow mandrel which may be lowered into a tubing string having annular channelways at tubing joints, a sleeve slideable on said mandrel, said sleeve being provided with a plurality of recesses, dogs carried by said sleeve in said recesses, a cam forming a part of said mandrel, means to move said mandrel relative to said sleeve to move said cam into engagement with said dogs to move the dogs outwardly into locking engagement with the tubing joint, the dogs having a thickness greater than the distance between the inner wall of the tubing string and the outer surface of the cam on the mandrel, and a garter spring engaging said dogs and tending to hold said dogs in their retracted positions.

7. In combination, a hollow mandrel which may be lowered into a tubing string having annular channelways at tubing joints, a sleeve slideable on said mandrel, said sleeve being provided with a plurality of recesses, dogs carried by said sleeve in said recesses, means to move the mandrel relative to said sleeve, means whereby the movement of said mandrel will move the dogs outwardly into locking engagement with the tubing joint and a sealing cup supported by said sleeve to seal the space between said sleeve and the tubing string.

8. In combination, a hollow mandrel which may be lowered into a tubing string having annular channelways at tubing joints, a sleeve slideable on said mandrel, said sleeve being provided with a plurality of recesses, pivoted dogs carried by said sleeve in said recesses, a spring tending to hold said dogs in their retracted position, means to move the mandrel relative to said sleeve to cause it to engage and move the dogs outwardly of the sleeve against the tension of said spring and into locking engagement with

the tubing joint and a choke supported by said sleeve.

9. In combination, a hollow mandrel which may be lowered into a tubing string having annular channelways at tubing joints, a sleeve 5 slideable on said mandrel, said sleeve being provided with a plurality of recesses, dogs carried by said sleeve in said recesses, means to move the mandrel relative to the sleeve, means whereby the movement of said mandrel will move the dogs outwardly of the sleeve into locking engagement with the tubing string and a sealing cup and a choke supported by said sleeve.

10. In combination, a hollow mandrel which may be lowered into a tubing string having annular channelways at tubing joints, a sleeve 10 slideable on said mandrel, a plurality of dogs carried by said sleeve, said dogs when in retracted position projecting inwardly of said sleeve, means tending to move said mandrel relative to said sleeve so as to cause said mandrel to project said dogs outwardly of the sleeve, said dogs having a thickness greater than the distance between said mandrel and the main section of the tubing string so that said dogs prevent said mandrel from fully moving the dogs outwardly except when the dogs are first positioned opposite one of said channelways.

11. In combination, a hollow mandrel which 15 may be lowered into a tubing string having annular channelways at tubing joints, said mandrel having an enlarged portion thereon, a sleeve surrounding said mandrel and slideable thereon, dogs carried by said sleeve and projecting inwardly thereof when in retracted position, a cam surface forming a part of said mandrel, means tending to move said mandrel relative to said sleeve to position said cam surface behind said dogs and move them outwardly of said sleeve into engagement with the tubing string, said dogs being of a thickness greater than the distance between said enlarged portion and the main section of the tubing string so as to prevent the enlarged portion from moving behind said dogs, except 20 when said dogs are first positioned opposite one of said channelways.

12. A running-in mechanism whereby a well tool having a mandrel may be lowered into a tubing and secured to the tubing at a desired depth, including a rod, a wire line supporting said rod, a collar slideable on said rod, bowed springs secured to said collar and engaging the inner wall of the tubing, a stop to limit the upward movement of said collar relative to said rod, a sleeve provided with a cam surface supported by said springs, a latch member carried by said rod, said latch member carrying a latch adapted to engage said mandrel and support the same when the running-in mechanism is being lowered in the tubing, said wire line when raised lifting said rod and well tool while the collar is held stationary relative to the tubing so that the latch is engaged by said cam surface to thereby release said latch from the mandrel.

13. In combination, a wire line, a rod supported thereby, a sleeve supported by said rod, a mandrel, a second sleeve extending over the lower portion of said mandrel, a latch normally connecting said first sleeve to the upper portion of the mandrel, means connecting said first sleeve to the second sleeve so that all of the above named parts may be lowered as a unit into a well tubing, dogs carried by the second sleeve to engage channels in the tubing when the dogs are

released, means to hold the dogs in retracted position as the wire line and parts carried thereby are lowered, means to release the mandrel from the first sleeve when the wire line is raised, means to actuate the mandrel when it is released by the first sleeve, cam means carried by the mandrel tending to actuate said dogs when the mandrel

is released so as to project said dogs into said channel in the tubing when the dogs have been raised adjacent to the channel, and means to thereupon release the means connecting the first and second sleeves so that the first sleeve may be removed from the tubing.

RAYMOND G. TAYLOR, JR.
